UNITED STATES PATENT OFFICE

ARNOLD RUTISHAUSER, OF ZURICH, SWITZERLAND

PROCESS OF AND DEVICE FOR MANUFACTURING HOLLOW BODIES BY MEANS OF
FIBROUS MATERIALS

Application filed May 16, 1931, Serial No. 537,894, and in Germany May 27, 1930.

Heretofore processes of manufacturing hollow bodies, such as bottles and other containers, by means of fibrous materials have been known. According to these processes 5 the fibrous material in suspension in a liquid is introduced into a completely closed pervious mould in such a way that said material will be discharged from the mould through a tube within and near the bottom of the latter. In this operation the walls of the mould will be charged with fibrous material from the bottom to the top. Another process heretofore known has for its object to use a receptacle arranged above the mould and 10 serving to increase the pressure of the liquid, the formation of the hollow bodies being effected from top to bottom. According to these known processes the hollow bodies are first moulded, whereupon gaseous compressed fluid is forced into the mould for the 15 purpose of finishing the moulding and drying the hollow body.

The processes above mentioned are objectionable in that they are applicable only for 20 the manufacture of hollow bodies of relatively little height, because the local position of the entrance of fibrous material invariable in height and the static pressure decreasing with the height enable a homogeneous deposit of fibrous material of uniform thickness to be obtained within certain narrow 25 limits only.

An apparatus is also known for the manufacture of pipes of fibrous material which 30 uses a mould with a stationary position and a movable part in connection with a core, which determines the bore of the pipe and which remains in the pipe for drying. The movable part of the mould is under pressure of weights 35 which are of influence only upon the density of the deposit, but not upon the height of the zone of deposit.

My present process permits of avoiding the 40 objections mentioned and manufacturing hollow bodies of unlimited length by the fact that the formation of the walls of the hollow bodies, that is the zone of deposit of fibrous material, is made independent from a special filling pipe by producing a level of liquid 45 adjustable from outside within the mould.

A further feature of the present process consists in using, simultaneously with the formation of the walls, a gaseous compressed fluid for finishing and drying the moulded article. A device for carrying the process according 55 to my invention into effect is illustrated by way of example in the accompanying drawing, wherein:

Fig. 1 is a vertical sectional view of the device showing the operation thereof during 60 the formation of a hollow body.

Fig. 2 is a vertical sectional view of the device after the completion of the moulding operation.

Fig. 3 is a transverse section on line I—I, 65 showing the unfoldable mould.

Referring to the drawing, *a*1 is a pipe through which fibrous material in suspension in liquid is forced under pressure into a receptacle *a*2 provided with a water-gauge *a*3 70 and from which leads a pipe *a*5 provided with a valve *a*4.

*b*1 is a pipe for gaseous compressed fluid, comprising telescoping sections *b*2 and *b*3. *c*2 is a branch pipe leading from the gaseous 75 fluid pipe *b*1 and provided with a valve *c*1.

*d*1 is the completely closed pervious mould, which is adapted to be unfolded for the purpose of enabling the hollow body to be taken from the mould after the moulding thereof. *d*2 is a piston made of the cross section of the mould *d*1 and rigidly connected to a stationary supporting pipe *d*3.

A lifting device *e*, such as a windlass or the like, is provided for moving the mould vertically. The edges of the mould are provided with hinges *d*'1, enabling the mould to be unfolded as shown in Fig. 3. The walls of the mould are provided with extensions *d*''1, which upon folding the mould are brought and held together by means of suitable fastening devices *d*'''1.

For the manufacture of a hollow body I proceed as follows: Fibrous material in suspension in a liquid is continuously introduced under pressure into the receptacle *a*2, said material flowing through the pipes *a*5 and *d*3 into the mould *d*1. During the formation of the hollow body the level of liquid in the mould will be held on a de- 100

terminate height N with relation to the piston d_2 by adjusting the supply of liquid. The level N of the liquid which corresponds to the zone of deposit of fibrous material 5 may be determined experimentally for a hollow body of determinate cross section. During the moulding process compressed gaseous fluid, for instance compressed air, steam or the like, is introduced through the pipe b_1 10 for the purpose of acting from inside on the moulded part of the hollow body. Owing to the fact that the compressed fluid is also in communication with the receptacle a_2 the level of the liquid will remain invariable in 15 proportion as liquid is supplied through the pipe a_1 according to the progressive lifting of the mould d_1 . By adjusting the lifting speed of the mould I am enabled to adjust the thickness and density of the deposit 20 formed, that is the walls of the hollow body. In the uppermost position the moulding of the hollow body will be complete. Towards its upper end said hollow body will be dried to an increased degree. In order to quickly 25 complete the drying process in the lower part of the body, the liquid pipe a_5 will be closed by means of the valve a_4 and the valve c_1 opened for introducing the compressed gaseous fluid through the pipes c_2 and d_3 into the 30 lower part of the mould d_1 , provided that the pressure of gas and the perviousness of the moulded article are such that the gas, in spite of the direct communication through b_1 , b_2 and b_3 , will force the liquid contained in 35 the pipes c_2 , a_5 , and d_3 into the mould d_1 . For the purpose of removing the hollow body from the mould the latter will be unfolded as shown in Fig. 3, whereupon the mould is moved back to its lower-most position and 40 the operation repeated as described. The length of the hollow body to be manufactured will be obtained as desired by limiting the lifting stroke of the mould. For the purpose of facilitating the removal of the 45 hollow body from the mould, the latter may be arranged also in a position different from the vertical position.

I claim:

1. A process of manufacturing hollow 50 bodies of fibrous materials, which consists in introducing liquid containing the fibrous material in suspension into a pervious mould, adjusting the height of the level of liquid within the mould from outside, for the purpose of influencing the height of the zone of 55 deposit of the fibrous material, and simultaneously introducing compressed gaseous fluid above the liquid within the mould while the walls of the hollow body are being formed, substantially as described.

2. A process of manufacturing hollow 60 bodies of fibrous materials, which consists in introducing liquid containing the fibrous material in suspension into a pervious mould, adjusting the height of the level of liquid

within the mould from outside, for the purpose of influencing the height of the zone of deposit of the fibrous material, introducing compressed gaseous fluid above the liquid within the mould while the walls of the hollow body are being formed, and subsequently after the completion of said walls introducing compressed gaseous fluid into the mould from below, substantially as set forth. 70

3. A process of manufacturing hollow 75 bodies by means of fibrous materials introduced in a pervious mould as a liquid containing the fibrous material in suspension, which consists in adjusting the height of the level of liquid within the mould from outside, for the purpose of influencing the height of the zone of deposit of the fibrous material, substantially as set forth. 80

4. In a device for manufacturing hollow 85 bodies by means of fibrous materials brought in a completely closed pervious mould with a stationary piston forming the bottom wall of said mould, the combination of means for displacing the mould with relation to said piston, a receptacle containing the fibrous material in a liquid, a pipe leading from the bottom of said receptacle through the piston into the mould and supporting said piston, in such a way that the receptacle and mould will be arranged to form communicating vessels, and means for adjusting the height of the level of liquid in said receptacle, substantially 90 as set forth. 95
